UNITED STATES PATENT OFFICE.

WILLARD A. CLARKE, OF STILLWATER, MINN., ASSIGNOR TO THE NORTH-WESTERN MANUFACTURING AND CAR COMPANY, OF SAME PLACE.

WATER-GAGE.

SPECIFICATION forming part of Letters Patent No. 278,223, dated May 22, 1883.

Application filed March 13, 1883. (No model.)

To all whom it may concern:

Be it known that I, WILLARD A. CLARKE, a citizen of the United States, residing at Stillwater, in the county of Washington and State of Minnesota, have invented certain new and useful Improvements in Water-Gages, of which the following is a specification, reference being had therein to the accompanying drawings.

10 Figure 1 is a side elevation of the gage when attached to the end of a boiler or to a plane vertical wall. Fig. 2 is a side elevation of the device when attached to a curved wall. Fig. 3 is a longitudinal section of the upper connecting-tube and a portion of the gage-tube. Fig. 4 is a vertical section on the line yy , Fig. 3.

In the drawings, A represents a portion of a steam-boiler sufficient to illustrate the method of applying my improved gage thereto. The 20 boiler is tapped or provided with a threaded aperture at a , and into this is fitted one part of the gage-support. This latter is constructed of the tubular part B, an expanded sleeve or chamber, C, and a tubular extension, D. The 25 part B is provided with a screw-thread, d , by means of which it is joined to the boiler, and with a valve-seat, b' , at the outer end of the inner tubular passage, b^2 . In the tubular projection D there is mounted a valve, E, the stem 30 e of which engages with said tubular part D by a screw-thread at e' , there being a hand-wheel at e^2 , of the usual character. The valve-stem e is mounted across the sleeve or expanded chamber C, and bears directly against the 35 valve-seat b' .

The gage-tube is represented by F, it being made of glass, and it may be in the details of its construction of any of the usual forms. At the upper end it is seated in a tubular socket-piece, G, there being a clamping-nut, g , and suitable packing, g' , of any preferred character, to form a perfect union. The tubular socket-piece G communicates with a chamber, H, formed in a tube, H' , situated at an angle 40 to the part G. The last-said part, H' , fits snugly in the sleeve or chamber C, it being situated transversely across the line of the tubes B and D. It is provided at its outer end with a screw-thread, as shown at h , by which 45 it there engages with a cap-nut, H^2 , having a

thread, h' , to engage with the thread h , and having also a flange or cap, h^2 , which closes tightly the outer end of the sleeve or chamber at C. The walls of the part H' are cut away, as shown at h^3 h^4 , to permit the passage through 55 it of the valve-stem e . The parts cut away are long enough to allow sufficient play or oscillation of the part H' , and therefore of the lower part of the gage-support.

The water-tube F is supported at the lower 60 end in devices substantially similar to those above described—that is to say, there is at said lower end a tubular part, I, connected with the boiler by a screw-thread, i , a sleeve or cylinder, J, an outward tubular projection, 65 K, a tubular socket, L, a tubular part, M, situated at an angle to the part L, slots m in the wall thereof, a cap-nut, M' , and a valve, N, and valve stem n , passing through said slots. This support at the lower part of the gage-tube, it will also be seen, can rock through a large arc on an axis transverse to that of the tubular parts I and K. With devices of this construction I am enabled to attach the water-gage tube to the side of a boiler with greater 70 ease and accuracy than are incident to devices for this purpose heretofore used.

Heretofore it has been necessary to bring the upper and lower supports for the gage-tube into line by rotating the tubular parts 80 corresponding to those shown at B D and I K. This has necessitated much trouble and caused great inconvenience. My gage-support is readily adjustable to any angle of inclination at which it may be convenient or desirable to put 85 the water-tube proper. I provide a universal joint or coupling with the boiler for the tube, both at the upper and the lower ends, so that it can be, as said, situated on any necessary line. The tubular parts B D and I K can be 90 turned more or less on their longitudinal axes, and the parts G H' and L M can be turned more or less upon the axes of the parts H and M. This being true, it will be seen that the tube F can be readily arranged upon any de- 95 sired line, and can be adjusted for any position. At the bottom of the support for the lower end an escape-cock, O, is provided, to allow the water to escape from the gage-tube when necessary. Preferably the threaded 100

parts *b* and *i* on the tubular portions are conical or tapering, so as to engage tightly with the threaded apertures in the boiler.

What I claim is—

1. In a water-gage for a steam-engine, the combination of a gage-tube, an attachment which communicates with the boiler below the water-line, an attachment which communicates with the boiler above said line, and devices at the ends of the gage-tube for connecting it to said attachments, which connecting devices can be moved into different angular positions relatively to the axis of the attachments which communicate with the boiler, substantially as set forth.
2. The combination of an attachment communicating with the boiler, the gage-tube, and a support for the end of the gage-tube, which support communicates with the interior of said boiler attachment, and which can be moved relatively to the axis thereof, substantially as set forth.
3. The combination of a tubular attachment for the boiler, a tubular support for the end of the gage-tube, and a connecting-tube situated transversely to the axis of the tube which is connected with the boiler, and loosely connected with the last-said part, whereby it can be adjusted to different positions, substantially as set forth.
4. The combination of the gage-tube *F*, the tube *B*, communicating with the interior of the boiler at the lower end of tube *F*, the tube *I*, communicating with the boiler at the upper end, and connecting devices between the water-tube and the tubes *B* and *I*, which hold the tube in a plane other than that of the tubes *I* and *B*, and which can be adjusted to different positions relatively to the tubes *I* and *B*, substantially as set forth.
5. The combination of the water-tube, the tubes *B* and *I*, the sleeves or chambers carried by said tubes *B* and *I*, and the tubes which connect the tube *F* with tubes *B* and *I*, and which are mounted in the sleeves or chambers carried by the tubes *B* and *I*, substantially as set forth.

6. The combination of the gage-tube, the tubes at the ends thereof communicating with the boiler, the adjustable devices which connect the gage-tube with those communicating with the boiler, and the valve-stem arranged to limit the movements of the connecting devices, substantially as set forth.

7. The combination of the gage-tube, the tubes at the end thereof communicating with the boiler, and the devices which connect the end of the gage-tube with those communicating with the boiler, said connecting devices having movable supports situated across the interior passages of the tubes which communicate with the boiler, and provided with passages to allow the insertion of the valves, substantially as set forth.

8. The combination of the gage-tube, the tube *B*, having the sleeve or cylindrical support *C*, and the devices which connect the gage-tube with the tube *B*, having the tube *H'* fitted within the cylindrical support *C* and adapted to move therein, substantially as set forth.

9. The combination of the gage-tube, the tube *B* at the end thereof, the sleeve or cylindrical support *C*, the interior of which communicates with the interior of the boiler, and the tube *H'*, situated at an angle to the gage-tube, and adapted to fit and to be moved in the sleeve or cylindrical support *C*, substantially as set forth.

10. The combination of the gage-tube, the cylindrical or tubular supports *C* and *J*, communicating with the interior of the boiler, and situated at an angle to the gage-tube, and the tubes connected to the ends of the water-tube, and fitted within said cylindrical or tubular parts *C* and *J*, and adapted to be adjusted therein around the axis of said tubular support, substantially as set forth.

In testimony whereof I affix my signature in presence of two witnesses.

WILLARD A. CLARKE.
